UNITED STATES PATENT OFFICE

2,366,416

HEATER

Henry J. De N. McCollum, Chicago, Ill.

Application June 5, 1943, Serial No. 489,768

7 Claims. (Cl. 126—116)

My invention relates to heaters and more particularly to heaters of the internal combustion type commonly used in airplanes.

In internal combustion heaters it is common to provide a muffler to eliminate objectionable noise resulting from heater operation and I have found that a muffler having a single open muffling chamber which is acoustically coupled to the gas passages through the heater is adequate for this purpose, provided the muffling chamber is maintained at substantially uniform pressure regardless of minor explosions or irregular burning of the combustible mixture in the heater. Where the muffler chamber is relatively small, it is only possible to prevent the pressure in this chamber from rising with each irregularity in combustion by maintaining a substantially free and open communication between this muffler chamber and atmosphere.

This is ordinarily accomplished by providing relatively free flow of secondary air through the muffler, this secondary air being discharged into the gas passages by way of the acoustic couplings between these passages and the interior of the muffler. This arrangement has the disadvantage that it materially decreases the efficiency of the heater, as the acoustic couplings between the muffler and gas passages must be adjacent the combustion chamber of the heater for best results and the discharge of large quantities of secondary air into the hot gases leaving the combustion chamber materially cools these gases and decreases the heat transfer from these gases to the heat exchanger and ventilating air.

Where the muffler chamber is made large enough so that the pressure therein will not increase materially with variations in combustion, no communication is required between this chamber and atmosphere to make it effective as an adequate muffler. However, such a chamber must be in communication with the gas passages through the acoustic couplings between the interior of this chamber and these passages. Under certain conditions of heater operation, a combustible mixture may accumulate in the large volume muffling chamber and if this mixture be ignited, an explosion may occur which will injure or destroy the heater. An object of my invention is to overcome these disadvantages of the large muffling chamber.

Another object of my invention is to provide a heater having a large muffling chamber and wherein means is provided for a slow flow of air through the muffling chamber to prevent the formation of a combustible mixture therein.

Another object of my invention is to provide a heater having new and improved means for preventing gasoline or gasoline vapors from entering the ventilating air delivered by the heater to the cabin or other space or spaces to be heated.

Another object of my invention is to provide a simple, inexpensive, efficient and durable heater which may be manufactured by conventional equipment and methods and which may be easily disassembled and reassembled for inspection, cleaning and repair.

Other objects and advantages will become apparent as the description proceeds.

In the drawing:

Fig. 1 is a longitudinal, sectional view through a preferred embodiment of my invention; and
Fig. 2 is a partial, longitudinal, sectional view of a modified form of my invention.

In Fig. 1, I have shown a heater comprising a combustion chamber 10 having an annular wall 12 provided with a flange 14 attached by screws 16 to a ring 18 forming one end of a heat exchanger indicated generally by reference character 20. The screws 16 also serve to attach the combustion chamber and heat exchanger to brackets 22 attached to a cylindrical heater casing 24 by means of screws 26. The opposite end of the heat exchanger has a similar ring 28 attached to brackets 30 by screws 32, which also serve to secure an end plate 34 to the ring 28. The brackets 30 are attached to the casing 24 by screws 36.

The heat exchanger 20 is shown as being of the type described and claimed in my co-pending application, Serial No. 464,451, filed November 4, 1942, although other forms of heat exchanger may be used in lieu thereof. The heat exchanger shown comprises, in addition to the rings 18 and 28, a tubular shell 38 which is corrugated to form gas passages 40 and to clamp the bases of longitudinally extending fins 42 between the corrugations forming the gas passages. The fins 42 project into the annular ventilating air passage 44 formed between the shell 38 and casing 24 and serve to transmit heat to the ventilating air flowing through this passage.

The lefthand end of the casing 24 is connected to a pipe 46 which receives air from a ram, blower, or any other suitable means. This ventilating air flows around the combustion chamber 10 and through the annular passage 44 and absorbs heat from the walls of the combustion chamber and the fins 42 and shell 38 of the heat exchanger. Most of the heated ventilating air flows from the righthand or outlet end of the

casing 24 into an airplane cabin or through a duct system having selected outlets arranged in the same or different spaces. A small portion of the heated ventilating air enters the inlet end 48 of a combustion air pipe 59 leading to the air inlet of the carburetor 52 where it is mixed with fuel to form a combustible mixture. A pipe 54 connects the carburetor 52 with any suitable source of fuel.

The mixture of fuel and air formed in the carburetor 52 leaves this carburetor by way of induction tube 56, having an end 58 located in the lefthand portion of combustion chamber 10, where it is ignited by an electrical igniter 60 located in a pocket at one side of the combustion chamber and communicating therewith through openings 62 and 64. A spiral C-shaped ring 66 serves to direct any liquid fuel delivered to the combustion chamber into the opening 62 for vaporization and ignition by the igniter 62. The re-igniter 68 is provided to maintain combustion after the igniter is cut out by the usual thermostatic switch. The particular structure and arrangement of the combustion chamber and its associated parts is claimed in my co-pending application, Serial No. 481,835, filed April 5, 1943, and my earlier applications therein referred to.

The hot products of combustion issuing from the combustion chamber are directed into the lefthand ends of gas passages 49 by the head or end wall 70 of a muffler indicated generally by the reference numeral 72. As these gases flow along the passages 49, they give up heat to the heat exchanger and the cooled gases then pass into an outlet chamber 74. This outlet chamber communicates with atmosphere through an outlet pipe 76, an outlet fitting 78, and any suitable exhaust pipe attached to the threaded end of this fitting.

The muffler 72 is preferably formed of sheet metal and has a cylindrical wall 80 which cooperates with the shell 38 of the heat exchanger to form the gas passages 49. The rear end of this muffler is provided with a sheet metal wall 82. The walls of this muffler form a single muffling chamber which is acoustically coupled to the gas passages 49 through a single annular row of openings 84 formed in the cylindrical wall 80 adjacent the head end of the muffler. This muffling chamber requires no stainless steel wool or glass wool, or other sound absorbing material, such as commonly provided in the mufflers used in connection with this type of heater. The capacity of this muffling chamber is sufficiently great so that the pressure of any gas or air contained therein will not be materially increased by irregularities in combustion and the muffler will effectively absorb the objectionable noises resulting from heater operation.

Since this muffler is connected through the openings 84 with the gas passages, it would be possible for unburned combustible mixture discharged from the combustion chamber to seep into the muffling chamber unless special means were provided to prevent such seepage. I prevent seepage of combustible mixture into the muffling chamber by providing a slow flow of secondary air through this chamber. This secondary air passes through the openings 84 into the gas passages 49 and tends to reduce the temperature of these gases and thereby decrease heater efficiency by decreasing the heat transfer between these gases and the heat exchanger.

A feature of my invention, however, lies in the

fact that in my novel heater much less secondary air is discharged into the combustion gases than is required by the usual heater so that the operating efficiency of my heater is not appreciably impaired by the discharge of secondary air into the products of combustion.

A small diameter pipe 86 is secured to the rear wall 82 of the muffler and projects through the plate 34 which closes the righthand end of the heat exchanger. This pipe is in open communication with the righthand end of the casing 24 so that ventilating air can flow through this pipe into the interior of the muffler 72. Since my heater is so designed that only a very small quantity of air flows through the muffler, under some conditions of operation gasoline fumes might find their way into the ventilating air unless special means were provided to prevent such an occurrence. I shall now describe this special means.

The pipe 86 is provided with a restriction 88 and also with an annular series of openings 90 which connect the interior of the pipe on the muffler side of the restriction 88 with the outlet chamber 74. The restriction 88 provides a relatively small opening through which the air flows rapidly so that no gasoline fumes can pass through this opening into the ventilating air. In order, however, to create the desired rate of flow through the restriction 88, it is necessary to pass more air through this restriction than it is desirable to discharge into the gas passages 49 as secondary air. The openings 90 permit most of the air flowing through the restriction 88 to pass into the outlet chamber 74 where it performs the desirable function of diluting the gases in this chamber and in the exhaust system connected therewith sufficiently to prevent combustion therein. The air passing from the tube 86 through openings 90 and into outlet chamber 74, however, has no effect on the efficiency of the heat exchanger and only an extremely small quantity of air is discharged into the gas passages 49 through the openings 84.

The air flow through the muffler is extremely slow and just sufficient to prevent the accumulation of an explosive mixture therein.

Because the flow of air through the muffler is very slow, this air flow has little cooling effect on the head end of the muffler which is exposed to the heat of the combustion chamber and the hot gases issuing therefrom. In some sizes and designs of heater this heat will not be sufficiently intense to injure the head end of the muffler, whereas in other designs it is desirable to protect the head end of the muffler by a layer of insulating material, as shown in Fig. 2. In this figure, a disc 100 is attached by screws 102 to the end wall 70' which corresponds to the end wall 70 of the embodiment of Fig. 1.

My novel heater may be made of conventional materials and by conventional equipment and methods. The various parts of the heater are of rugged construction capable of affording long and trouble-free service and these parts are so constructed and arranged that they may be easily disassembled and reassembled for inspection, cleaning and repair. While I have described my heater as particularly adapted for use in airplanes because of its high heat output for a given size and weight, it is equally capable of use for other purposes.

My invention may assume numerous other forms in addition to those shown and described in detail herein and my invention includes all

variations and modifications falling within the scope of the appended claims.

I cla'm:

1. A heater of the class described, comprising a casing having one end adapted for connection to a source of air, a combustion chamber in said casing, a heat exchanger connected to said combustion chamber and receiving hot products of combustion therefrom, a muffler located in said heat exchanger and having a head end adjacent said combustion chamber, said muffler having a large muffling chamber, openings in the head end of said muffler forming acoustic couplings between said muffling chamber and said combustion chamber, means providing an orifice connecting the other end of said muffling chamber with the interior of said casing, and means interposed between said orifice and said muffling chamber for diverting to an exhaust outlet most of the air passing through said orifice before reaching said muffling chamber.

2. A heater of the class described, comprising a combustion chamber, a muffler for absorbing sound created by combustion in said chamber, said muffler having a muffling chamber, a heat exchanger receiving hot products of combustion from said combustion chamber, means for directing ventilating air over said heat exchanger, means including openings connecting said muffler w'th said combustion chamber and with the interior of said casing for creating a flow of secondary air through said muffler, means for passing more air through the opening between the muffler and casing than between said muffler and combustion chamber, and means for exhausting excess air passing through said last-named opening.

3. A heater of the class described, comprising a casing connected to a source of ventilating air, a heat exchanger in said casing, a combustion chamber connected to said heat exchanger and delivering hot gases thereto, a muffler having a muffling chamber, means providing openings forming acoustic couplings between said chambers and permitting flow of secondary air from said muffling chamber into hot products of combustion from said combustion chamber, means including an orifice connecting said muffling chamber with the interior of said casing, means for causing more air to flow through said orifice than enters said muffling chamber, and means for exhausting excess air flowing through said orifice.

4. A heater of the class described, comprising a casing having an end adapted for connection to a source of air supply, a combustion chamber, a heat exchanger in said casing receiving hot gases from said combustion chamber, a muffler having a muffling chamber, means forming an acoustic

coupling between said muffling chamber and said combustion chamber, said means affording open communication between said chambers, a pipe connecting said muffling chamber with the interior of said casing whereby air can flow from said casing into said muffling chamber, means including an opening intermediate the ends of said pipe for causing more air to enter said pipe than is discharged by said pipe into said muffling chamber, and means for exhausting excess air entering said pipe.

5. A heater of the class described, comprising a casing having one end connected to a source of air, a heat exchanger located in said casing and having gas passages therein, means for supplying hot gases to said passages, a muffler located in said heat exchanger, said muffler providing a muffling chamber, means providing an acoustic coupling between one end of said chamber and said passages, said means permitting fluid flow between said passages and muffling chamber, means providing an outlet chamber in communication with said gas passages, a pipe extending through said outlet chamber and connecting said muffling chamber with the interior of said casing, and an opening in said pipe for diverting into said outlet chamber part of the air entering said pipe from said casing.

6. A heater of the class described, comprising a casing connected to a source of air, a combustion chamber, a heat exchanger located in said casing and receiving hot gases from said combustion chamber, said heat exchanger having gas passages therethrough, a muffler located in said heat exchanger and having a muffling chamber, means providing an acoustic coupling between said muffling chamber and one end of said passages, tubular means for admitting air from said casing to said muffling chamber, and means connecting an intermediate portion of said tubular member with the outlet end of said gas passages.

7. A heater of the class described, comprising a casing adapted for connection to a source of air, a combustion chamber in said casing, a heat exchanger connected to said combustion chamber, a muffler associated with said heat exchanger, said muffler having a head end exposed to heat from said combustion chamber, insulating means for said end, acoustic couplings adjacent said end, and means for causing secondary air to flow through said couplings, said means comprising a connection between the other end of said muffler and the interior of said casing, means for causing more air to flow through a part of said connection than is delivered to said muffler, and means for exhausting excess air flowing through said part.

HENRY J. DE N. MCCOLLUM.
